(57) **CLAIM**

I claim the ornamental design for an optics cleaning kit, as shown and described.

DESCRIPTION

FIG. 1 is a perspective view of an optics cleaning kit according to the present invention;

FIG. 2 is a front view thereof;

FIG. 3 is a rear view thereof;

FIG. 4 is a right side view thereof;

FIG. 5 is a left side view thereof;

FIG. 6 is a top view thereof facing front;

FIG. 7 is a bottom view thereof facing rear;

FIG. 8 is a separated view showing upper and lower elements;

FIG. 9 is a front view of the invention of FIG. 8;

FIG. 10 is a rear view of the invention of FIG. 8;

FIG. 11 is a right side view of the invention of FIG. 8; and,

FIG. 12 is a left side view of the invention of FIG. 8.

The broken lines in the drawings illustrate portions of the optics cleaning kit and form no part of the claimed design.
